SHUTTLE BRUSH

John A. Matson, Troy, N. H.

Application January 5, 1944, Serial No. 517,096

4 Claims. (Cl. 139—218)

This invention relates to shuttles, especially to those used in weaving woolen yarn or other similar yarn which carries along a certain amount of short fibre or fuzz which may get into the shuttle eye and clog it and for any other shuttles where a gentle tension or holding back on the yarn is desirable.

In the past, and in addition to the various types of friction pads in the shuttle eye and fur which engages the yarn mass on the bobbin, bristle brushes extending into the bobbin chamber in position to intercept the thread have been extensively used.

The usual method of positioning these brushes is to bore a hole through the side of the shuttle leading into the bobbin chamber and then force a bunch of bristles into this hole either smearing the inside of the hole or the outside of the bristles with adhesive so that they stay in position.

When the bristles wear down and it is necessary to replace them, it is a difficult task to clear the hole of bristles and adhesive and to do a good job, the shuttle must be taken out of service into a properly equipped shop.

My device is a bristle brush for shuttles and comprises a bunch of bristles and a holder therefor, the holder including a receiving member which when attached in position in the shuttle can remain in that position to receive a brush holding member which can be removed and replaced or both can be removed together and both can then be replaced. The brush holding member is preferably of a character which requires no adhesive to hold the bristles in place.

My preferred way of accomplishing this purpose is to have the two members so arranged that when the brush holding member is screwed into the receiving member, the bent part or the ends of the bristles which project through the bristle holding member will spread out or mushroom and be firmly squeezed in place between the two members.

Preferably there is a hole through the bristle holding member at an angle with its axis and preferably a loop of a bunch of bristles is pulled through the hole by a thread and the thread is then stitched through and through the loop or tied around it.

The holding and the receiving members may be made in various ways and the receiving member may be attached to the shuttle in various ways. It may be easily removable or permanently fixed in position but the brush holding member is so attached that it will not be loosened by the

shaking of the loom but at the same time it can easily be removed, as by the use of a screw driver and a wrench, for replacing the worn bristles or to be itself replaced.

In the drawing,

Fig. 1 is a plan view of the eye end of a shuttle with my device in place.

Fig. 2 is an elevation from the side of the shuttle eye of the same shuttle shown in Fig. 1, part of the wall being broken away to show a brush in the opposite interior wall.

Fig. 3 is an elevation of the brush holding member and Fig. 4 is an elevation of the receiving member.

Fig. 5 is a sectional view through part of a shuttle wall and through the receiving member, the brush holding member being shown in elevation and not in section.

Fig. 6 is an isometric view showing a brush holder removed from the receiving member with the bend of the bristles flattened out or mushroomed as they are when the brush holder is in position.

Fig. 7 is a similar view to Fig. 5 of a modified construction of receiving member and brush holder.

Fig. 8 is another view similar to Fig. 5 of still another modification.

Fig. 9 is a view similar to Fig. 5 showing the same brush holder and receiving member attached to a shuttle with a thicker wall.

In the drawing, S represents a shuttle in which is a bobbin chamber 40 in which is positioned the bobbin B with its tip 43 near the front of the bobbin chamber.

41 and 42 are the side walls of the bobbin chamber.

P, P, represent bunches of bristles which are preferably double the length required and are bent at 7 as shown in Fig. 3. D represents the thread.

Through a side wall of the shuttle and extending into the bobbin chamber 40 are one or more holes such as 6 each of which at the outside is counter-bored to form a concentric annular recess 5 and to form an inwardly extending annular rib 16.

The bristle brush unit H is formed of several parts and includes especially a receiving member F with a head 15 which preferably fits snugly inside the recess 5 and a shank 12 which fits fairly close in the hole 6. As shown this shank 12 is threaded on the outside 18 and in it is the axially positioned dead end hole 14 with interior threads 13. W is a washer, of which one or more

may be used, which fits over the shank 12 against the inside of the side of the shuttle in the bobbin chamber between it and a holding nut C which is provided with interior threads 38 which engage the outside threads 18 of shank 12 of member F.

There is a turning slot 10 for a screw driver in head 15.

There are preferably two or more brushes H, H, and the bunch of bristles of each preferably rakes or slopes forward towards the eye end of the shuttle and either down under the bobbin or up over it as shown in Figs. 1 and 2.

The brush holding member M has a head 1 which preferably is of hexagonal or other similar shape so that a wrench can easily grasp it and a neck 2 through both of which extends a bristle hole 4 which preferably is bored at an angle and which, on the inside, is preferably countersunk at 44. The neck 2 has outside threads 3 adapted to engage the inside threads 13 on the shank 12 of the receiving member F.

The neck 2 is preferably not quite as long as the depth of dead end hole 14 in the shank 12 of the member F.

With the above construction, there is an annular, inwardly projecting rib 16 of the holder receiving hole 6 and when the nut C is screwed up on the outside threads 18 of shank 12, either with or without the interposition of one or more washers such as W, the receiving member F is permanently fixed in place although it can be removed by unscrewing the nut C.

In first positioning a bunch of bristles such as P in a bristle hole 4, it is bent as at 7 and pushed or preferably pulled through the hole 4 in the neck 2 of the brush holding member M. It can conveniently be pulled through by thread 8 and as the bend 7 projects, this thread is sewed or twisted through and around it to form a bunch which is larger than the hole 4.

It may then be pulled back so as to partly rest in the countersunk part 44 in the end of neck 2. When neck 2 is screwed into the dead end hole 14, this part 7 with the sewing thread 8 is spread out and mushrooms as shown in Figs. 5 and 6 so that it cannot be pulled back. This also prevents any of the bristles from being pulled out individually by the thread as it runs off from the bobbin.

As hole 4 is at an angle and it is desirable that the brushes should rake or slope forward at an angle, the parts are preferably adjusted as follows:

With the parts assembled substantially as in Fig. 5, with head 15 in recess 5 and with brush holder M and nut C loosened, brush P with holder M is turned to the right position and while it is held in that position, receiving member F is turned on outside threads 3 of neck 2 as far as it will go, after which, the nut C is screwed up on the outside threads 18 of shank 12 thus pressing the washer W against the inside of bobbin recess 40 and squeezing annular rib 16 between head 15 and washer W thereby locking all the parts in place with the brush in the right position.

As shown in Fig. 9, two or more washers W, W, can be used on one or both sides of rib 16 to help in making the device fit shuttles with walls of different thicknesses.

It will be noted that the wall 42 of the bobbin chamber is thicker than that shown in Fig. 5.

In Fig. 7 is shown a variation of the above construction. A straight hole 19 with no recess

or rib 16 goes through the side of the shuttle into the bobbin chamber. This hole 19 is formed with threads 29 which engage outside threads 21 of a receiving member L which has a dead end hole 24 with inside threads 23 to engage outside threads 20 of the brush holding member O.

There is a bristle hole 26 bored at an angle through this member O and countersunk at 45 and it also has preferably a turning slot 25. Receiving member L also is preferably provided with a turning slot 22.

The operation is the same as in the other construction. The bristles P are bent at 7 and stitched at 8 and mushroom or spread at the end of the dead end hole 24.

In Fig. 8 is shown a modification of the construction shown in Fig. 7. As there shown, bristles A are drawn through tubular brush holding member R until they project from the end 39 where they may be stitched or twisted together or as shown, may be simply allowed to spread out as at 37 when this shell R, threaded on the outside at 36, is screwed into the dead end hole 32 having inside threads 34 and bored at an angle 25 into a receiving member T.

Receiving member T has outside threads 35 which engage inside threads 31 in a hole 30 bored straight through the shuttle wall.

In every construction, when the members of a brush are adjusted and fixed in place, the axis of the bunch of bristles and of the bristle hole is at an angle with the axis of the receiving member.

I claim:

1. The combination with a weaving shuttle having a bobbin chamber between its side walls, a brush hole through one of the side walls, and an annular recess on the outside concentric with the brush hole; of a receiving member for a bristle holding member, the receiving member having a head which enters the annular recess and a shank which enters the brush hole, the shank being formed with exterior screw threads and with a dead end hole with interior screw threads; a washer on the inside of the shuttle wall; a holding nut screwed onto the outside screw threads of the receiving member shank; and a bristle holding member having a head and a neck through both of which extends a bristle hole at an angle with the axis of the receiving member, the inner end of the bristle hole being countersunk and the neck having outside threads which fit the interior screw threads of the dead end hole in the receiving member shank and being shorter than the depth of the hole therein; and a bunch of bristles bent and extending through the bristle hole so that the bent part projects into the dead end hole in the shank, the bent part being stitched into a bunch positioned in the countersunk end of the bristle hole, the free ends of the bristles projecting beyond the head of the brush holding member.

2. The combination with a weaving shuttle having a bobbin chamber between its side walls, a brush hole through one of the side walls, and an annular recess on the outside concentric with the brush hole; of a receiving member for a bristle holding member, the receiving member having a head which enters the annular recess and a shank which enters the brush hole, the shank being formed with exterior screw threads and with a dead end hole with interior screw threads; a holding nut screwed onto the outside screw threads of the receiving member shank; a bristle holding member having a head and a neck

through both of which extends a bristle hole at an angle with the axis of the receiving member, the neck having outside threads which fit the interior screw threads of the dead end hole in the receiving member shank; and a bunch of bristles bent and extending through the bristle hole so that the bent part projects into the dead end hole in the shank, the bent part being stitched into a bunch, the free ends of the bristles projecting beyond the head of the brush holding member.

3. The combination with a weaving shuttle having a bobbin chamber between its side walls and a brush hole through one of its side walls; of a receiving member fastened in said brush hole and having a dead end hole with interior threads, a brush holding member with exterior threads engaging the interior threads of the dead end hole of said receiving member and having

a bristle hole extending entirely through it; and a bunch of bristles removably held in the bristle hole and with a bent part projecting therefrom into the dead end hole.

5. The combination with a weaving shuttle having a bobbin chamber between its side walls and having a plurality of brush holes through its side walls; of a plurality of brushes each including a receiving member fastened in a brush hole, a brush holding member axially adjustable with reference to the receiving member and perforated by a bristle hole, a bunch of bristles bent and extending through the bristle hole in the brush holding member so that the bent part projects to prevent the bristles from being pulled out when the parts are assembled but to allow them to be pulled out when the brush holding member is detached from the receiving member.

JOHN A. MATSON.
